United States Patent

Des. 235,754
Patented July 8, 1975

235,754

BOAT

Richard F. Berry, St. Louis County, Mo.
(6 Zinzer Court, St. Louis, Mo. 63123)

Filed Feb. 28, 1974, Ser. No. 446,611

Term of patent 7 years

Int. Cl. D12—06

U.S. Cl. D12—63

FIG. 1

FIG. 5

FIG. 6

FIG. 2

FIG. 3

FIG. 4

FIG. 1 is a perspective of a boat showing my new design;

FIG. 2 is a top plan view thereof;

FIG. 3 is a side elevational view thereof, the opposite side being identical thereto;

FIG. 4 is a bottom plan view thereof;

FIG. 5 is a front elevational view thereof; and

FIG. 6 is a rear elevational view thereof.

I claim:

The ornamental design for a boat, substantially as shown and described.
